UNITED STATES PATENT OFFICE.

JOSEPH S. KEMP, OF MAGOG, QUEBEC, CANADA.

FERTILIZER-DISTRIBUTER.

SPECIFICATION forming part of Letters Patent No. 268,410, dated December 5, 1882.

Application filed December 24, 1881. (No model.)

To all whom it may concern:

Be it known that I, JOSEPH SARGENT KEMP, a citizen of the Dominion of Canada, residing at Magog, in the county of Stanstead and Province of Quebec, have invented certain new and useful Improvements in Fertilizer-Distributors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in fertilizer-distributors, more especially in the manure-spreaders covered in the Letters Patent granted to me May 1, 1877, No. 190,220, Re-issued May 28, 1878, No. 8,254, and Letters 20 Patent No. 241,023, dated May 3, 1881.

The object of this invention is, primarily, to attain various rates of speed in the bottom-operating mechanism with reference to a given motion of the driving-wheels or their axle, 25 whereby the bottom or floor of the cart will be moved rearwardly at different speeds to the drum, so as to effect the distribution of varying quantities of fertilizing material to the acre as may be deemed necessary or advisable in view 30 of the requirements of the land or the strength of the fertilizer.

To this end my invention consists of parts substantially as hereinafter described, and fully set forth in the claims.

35 Referring to the drawings, Figure 1 is a plan view of my improved distributor. Fig. 2 is a side elevation thereof with one of the driving and carrying wheels removed and exhibiting the bottom-operating mechanism. Fig. 3 is a 40 detail view showing the arrangement of the coil-spring and wrist of the crank-arm in the slotted connecting-bar. Fig. 4 is an elevation of the improved spur-gear wheel having the several series of teeth, as described hereinafter, 45 and also showing a portion of the worm-shaft with its pinion; and Fig. 5 is a detail elevation of the worm-shaft with its worm and pinion, the sector, and bell-crank lever, and parts of the contiguous mechanism. Fig. 6 is a detail 50 view of the segment.

Corresponding parts in the several figures are denoted by similar letters of reference.

In the annexed drawings, A is the box or body; B, the endless chains; C, the slatted bottom; D, the toothed drum or spreader; E, 55 the driving and supporting or carrying wheels, and F the axle.

The axle freely revolves in bearings on the under side of the frame of the machine and receives near each end the driving-gears *j* and *v*, 60 securely keyed thereto. The pawl-and-ratchet mechanism for conveying motion from the wheels to the axle when the machine moves forward is connected, as heretofore, to the axle and hubs of the wheels E. The spur-gear *v* 65 meshes with the pinion *p*. The inner face of the latter is provided with teeth which can be made to interlock with similar teeth on the contiguous face of the hub of the gear-wheel L by means of the shipper S, pivoted at *e*, as 70 shown. The forward extremity of said shipper engages with the screw *h* on the shaft M, which extends across the forward part of the machine and carries at its opposite end the crank-arm O. The hand-lever *o* is secured to the shaft M 75 and serves, upon being raised, to partially revolve the said shaft to cause an outward movement of the shipper S, inducing the pinion *p* and gear-wheel L to clutch, by which motion 80 is conveyed from the axle to the toothed drum D through the train of gears *v*, *p*, L, N, and *s*.

When the load in the body of the cart is discharged the projection or finger *b* on the end board, H, will press on the trip-lever T, causing the latch *l*, connected thereto by the wire 85 *d*, to be swung on its pivot and be withdrawn from contact with the hand-lever *o*, thereby permitting the latter to fall, when, through the partial rotation of the shaft M, the shipper will disengage the jaws of the clutch to prevent 90 further rotation of the drum; and, further, the bottom-operating mechanism will be prevented from conveying motion to the bottom, as will be presently seen. After the load is discharged 95 the bottom is brought into place in the body of the cart by hand, and to this end the shaft Z, carrying the pulleys engaging with the endless chain, is provided. The shaft Z is also provided with the stop-wheel *r*, designed to act with mechanism, to be hereinafter described, 100

to prevent the bottom moving backward, except when the machine operates to distribute fertilizing material. In the present instance the crank which enables the operator to rotate the shaft J is secured to the stop-wheel r to obtain increased leverage.

All the foregoing recited parts, as well as several of the features to be presently described, are constructed and arranged substantially as described in the Letters Patent mentioned hereinbefore, and reference is made thereto for a fuller description of the parts and their operation.

Meshing with the pinion j, keyed to the axle F, as stated, is a spur-gear wheel, G, removably held on a stud, g, secured to the body A. This wheel is provided with two or more series of teeth annularly arranged on one of its sides with intervening spaces.

K marks the worm-shaft, having a worm, k, secured to its rear end, which meshes with the worm-gear wheel f, attached to the shaft f', carrying the polygonal wheel, upon whose surface is laid the slatted bottom as it is drawn backward through the operation of the machine. The forward end of the worm-shaft is fastened in a sleeve, which in turn is held free to rotate on the stud g. A portion of this shaft at its forward end is squared, and receives a pinion, G', capable of longitudinal motion thereon. This pinion G' is provided with a flange, g', which projects into the space between any two of the series of teeth on the gear-wheel G when the said pinion engages with the series immediately in front or inward of said space, and thus is held at a given point on the worm-shaft.

When it is desired to engage the pinion with the outermost series of teeth the said pinion is moved on the worm-shaft until it strikes against the pin k', when the adjustment is made and the pinion prevented from further backward movement. To make these several adjustments it is necessary to partially or wholly remove the holding-nut or other device for retaining the wheel G on its stud and slip the said wheel outward, so as to permit the pinion to be moved on the shaft to the desired position. By this arrangement of parts I am enabled to give to the worm-shaft various rates of speed from a given speed of the driving-axle, so as to effect the distribution of varying quantities of fertilizing material to the acre as may be required in view of the condition of the land or the strength of said fertilizing material. The necessity of extra sets of gears, as heretofore, to render the machine complete is avoided.

The worm-shaft receives an exteriorly squared sleeve, u, serving as a bearing for said shaft between the worm-gear and the squared portion, and is capable of vertical play in the slotted sector U, fastened to the body of the cart.

A bell-crank lever, W, is pivoted to the body A, the lower end of which is provided with a

lateral pin working in the slotted projection w of the sleeve u, as particularly shown in Fig. 5. To the upper end of this lever is fastened a connecting-bar, X, which extends to the forward part of the body, where it is held to the side thereof by a keeper, x. This keeper permits vertical play of the connecting-bar, but prevents lateral movement thereof. An additional keeper, x', may be provided, as shown in Fig. 2. The forward end of the connecting-bar X is slotted to receive a coil-spring, and in front thereof the wrist of the crank-arm O, which latter is secured to the shaft M, as stated hereinbefore.

Depending from the wrist of the crank-arm O is a connecting-rod, Y, whose lower end is attached to the forward extremity of a lever, y, pivoted at its opposite end to the body, as shown. This lever is provided with a lateral projection, y', which, when the machine is not acting as a distributor, engages with the teeth of the stop-wheel r.

Fig. 2 of the drawings shows the hand-lever o in an upright position, and held by the latch, the projection y' removed from the stop-wheel r, and the bottom-operating mechanism properly adjusted to cause the bottom to be moved backward upon giving a forward motion to the cart.

To disengage the bottom-operating mechanism from the bottom, the lever o is released from the latch I and drawn forward, when the crank-arm will depress the forward end of the connecting-bar X, partially rotating the bell-crank lever on its axis, whereupon the worm will be lifted out of contact with the worm-gear wheel, the worm-shaft having an upward movement in the slotted sector, and the sleeve at the forward end worm-shaft is partially rotated on the stud g. Simultaneously the connecting-rod Y, held to the crank-arm O, will cause the lever y to be depressed, when the projection y' will engage with the teeth of the stop-wheel to prevent backward motion of the bottom. It will now be seen that by moving the hand-lever o from the position shown in Fig. 1 to the upright position shown in Fig. 2 the entire machine will be thrown into gear to cause a proper distribution of fertilizing material upon giving a forward motion to the cart; and, on the other hand, the drum and bottom operating mechanisms will be thrown out of gear, and the bottom-holding mechanism into engagement by giving an opposite motion to the hand-lever, either automatically by the trip, as described hereinbefore, or by hand. Should the worm strike upon the teeth of the worm-gear wheel when the various mechanisms are thrown into engagement, the coil-spring in the end of the connecting-bar X will be compressed by the wrist of the crank-arm, whereby the hand-lever o can be brought to a vertical position, so as to engage with the latch. The forward motion of the wheels and consequent rotation of the worm will cause it to drop into proper engagement with the worm-gear wheel. By

this construction all damage or strain to the parts is avoided.

The several series of teeth on the gear-wheel must be so cut as to work with the single pinion G'.

If desired, an adjustable sleeve may be placed on the worm-shaft in the place of the pin k', so that as the parts become worn the said sleeve may be adjusted to prevent end-play of the said parts.

Having thus described my invention, what I claim, and desire to secure by Letters Patent, is—

1. The combination, with the rotating drive-
15 axle of a fertilizer-distributer, provided with a spur-pinion, and a movable bottom and its actuating-shaft, having a worm-gear secured to one end thereof, of a worm-shaft provided with a worm to mesh with the worm-gear, and
20 having a spur-pinion capable of longitudinal adjustment on said shaft, but prevented from revolving thereon, and the wheel G, journaled to the body A and having teeth on its periphery to mesh with the spur-pinion on the drive-
25 axle, and provided with two or more concentric series of cogs on one of its sides, substantially as and for the purpose set forth.

2. The combination, with the wheel G, removably held on the stud g, secured to the body
30 A, of the squared worm-shaft held to the stud g and provided with the pin, as shown, and the spur-pinion free to move longitudinally on said squared shaft and having the flange, substantially as described, and for the purpose set forth.

35 3. The combination, with the rotating drive-
axle of a fertilizer-distributer, provided with a pinion, and a movable bottom and its actuating-shaft, having a worm-gear secured to one

end thereof, of a squared worm-shaft provided with a worm to mesh with the worm-gear, a pin, as shown, and a spur-pinion free to move longitudinally on said squared shaft and having a collar or flange, g', and the wheel G, removably held on the stud g, secured to the body
45 A, having teeth on its periphery to mesh with the spur-pinion on the drive-axle, and provided with two or more concentric series of cogs on one of its sides, substantially as shown and described, and for the purpose set forth.

4. The combination, with the movable bottom and its actuating-shaft, provided with worm-gear wheel, of the worm-shaft adapted to be moved on its stud in a vertical plane, and provided with the worm and slotted sleeve,
55 the slotted sector, and the bell-crank lever connected to the slotted sleeve and having a bar extending to the forward part of the body, as shown and described, and for the purpose set forth.

5. The shaft M, having the crank-arm, the slotted bar provided with the coil-spring, the bell-crank lever, the movable worm-shaft provided with the sleeve, the bottom-actuating shaft provided with the worm-gear wheel, and
65 the movable bottom, in combination, for the purpose set forth.

6. The stop-wheel, the shaft M, provided with the crank-arm, the connecting-rod Y, and lever y, having the projection y', in combination,
70 substantially as shown and described, and for the purpose set forth.

In testimony whereof I affix my signature in presence of two witnesses.

JOSEPH SARGENT KEMP.
